UNITED STATES PATENT OFFICE.

ALBERT NELSON, OF SAN FRANCISCO, CALIFORNIA.

FIREPLACE DAMPER.

Application filed October 17, 1927. Serial No. 226,606.

This invention relates to a fire place damper, and its object is to provide a damper which will be so placed as not to interfere with the draft of the fire place, and to also be so placed as to secure it easily in the desired position.

It will be understood by those skilled in the art that it is common to build fire places with the lower part of the chimney of solid brick, while this brick only extends a short distance above the mantel, or in some cases as high as the ceiling, but from a point close to the top of the opening of the fire place a so called "patent flue" is used.

15 This patent flue consists of an interior fire clay pipe with an exterior galvanized pipe spaced a short distance from the interior pipe to give suitable insulation space.

20 These so called "patent flues" must rest upon some foundations, and ordinarily a cast iron plate is used for the support of said flue and this same plate is made use of for the support of the damper thereby allowing a sufficient amount of open chamber space a 25 short distance above the top of the throat of the fire place to not interfere with the drawing qualities of the flue.

Other objects of the invention will be apparent as the description proceeds.

30 An embodiment of the invention is shown in the accompanying drawings in which the same reference numeral is applied to the same portion throughout the several figures of the drawings and of which there may be modifications.

35 Figure 1 is a vertical sectional view through a brick fire place showing the patent flue in place, and showing the damper wide open,

40 Figure 2 is a plan view of the supporting plate for the patent flue,

45 Figure 3 is a side elevation of the supporting plate shown in Figure 2, a portion being broken away to show the lugs for holding the clay pipe central,

Figure 4 is a vertical sectional view through the damper holding ring, and

Figure 5 is a plan view of the damper holding ring.

50 The numeral 1 indicates the fire place; 2 the throat flue of the fire place; 3 the back wall of the fire place; 4 the front fire place wall; 5 the fire place mantel slab and 6 the chimney. The numeral 7 indicates the clay

pipe outside of which is placed the galvanized pipe 8.

The clay pipe 7 and the galvanized pipe 8 rest upon the plate 9. This plate is flat and has a circular flange 10 with a series of lugs 11 which hold the clay pipe in the proper position.

It will be understood by those skilled in the art that the clay pipe is placed inside the lugs 11 while the galvanized pipe 8 is placed just inside the flange 10 to allow the necessary insulation space to prevent over-heating the galvanized pipe.

The plate 9 has four holes 12 to 15 therein, which holes are placed in the proper position to meet the holes 16 to 19 in the lugs 20 to 23 of the damper ring 24. On one side 70 of the damper ring 24 has a shallow groove 26 to receive the pivot 27 of the damper 28. The damper 28 is of the common butterfly valve type with a supporting pivot pin 29 75 on the side opposite from the pin 27, the latter pin having a socket in which the squared rod 30 is secured by means of the set screw 31. The damper ring has a lug 32 on which the damper rests when it is turned horizontally, and it has a lug 33 to prevent the damper from being turned beyond the position shown in Figure 1.

In practice the damper rod 30 is installed 80 in a tube 34 which is built into the brick work of the chimney and a socket handle 35 just under the mantel sleeve is used to turn the damper, a set screw 36 holding the handle and rod 30 together. In practice it will be seen that the damper is installed high 85 enough above the fire place throat 2 to not interfere with the draft and it can be conveniently adjusted to any desired position by the use of the handle 35 which is installed in the most convenient position, 90 either that shown, or in some other position dependent upon the shape of the chimney and mantel.

It will also be seen that the damper can be placed in position in the ring before it is 100 assembled in place by putting the pivot pin 29 through the opening therefor in the ring and then allowing the pivot pin 27 to pass downwardly to its seat through the groove 26. The supporting ring 24 is bolted to the 105 underside of the plate 9.

Having thus described my invention, what I desire to secure by Letters Patent of the

United States is as follows, but modifications may be made in carrying out the invention as shown in the drawings and in the above particularly described form thereof, within the purview of the annexed claims.

- 6 1. A damper for fire places comprising the combination with the chimney throat of a supporting plate, a damper ring carried thereby, and a butterfly damper carried by 10 the ring and operable from a position in front of the fire place.
- 15 2. A damper for fire places comprising the combination with the chimney and its throat of a flue supporting plate, a damper ring carried by said flue supporting plate, a butterfly valve in said damper ring, a rod extending therefrom outside the chimney, and a handle for operating the rod whereby the damper may be adjusted in position.
- 20 3. A chimney damper comprising the com-

bination with a chimney having a fire place and throat of a flue supporting plate about the throat and smoke chamber of the chimney, a damper ring carried below the flue supporting plate, a damper carried by the 25 ring, and means extending outside the chimney for the operation of the damper.

4. A chimney damper comprising the combination with a chimney having a fire place with a constricted throat and enlarged smoke 30 chamber, a flue supporting plate above the smoke chamber, a flue supported thereby, a damper ring carried by said plate, a damper pivotally supported in said ring, and a handle extending through the chamber 35 for the regulation of the damper.

In testimony whereof I have hereunto set my hand this 10th day of October, A. D. 1927.

ALBERT NELSON.
